UNITED STATES PATENT OFFICE.

KARL JOHAN THORSBY, OF OAKLAND, CALIFORNIA, ASSIGNOR TO CALIFORNIA CORRUGATED CULVERT COMPANY, OF OAKLAND, CALIFORNIA, A CORPORATION OF CALIFORNIA.

METALLIC CULVERT.

1,017,847.

Specification of Letters Patent. Patented Feb. 13, 1912.

Application filed October 30, 1911. Serial No. 657,466.

To all whom it may concern:

Be it known that I, KARL JOHAN THORSBY, a subject of the King of Norway, residing at Oakland, in the county of Alameda and State of California, have invented certain new and useful Improvements in Metallic Culverts, of which the following is a specification.

My invention relates to the class of culverts, drain pipes, and the like, and especially to structures of this nature made of sheet metal.

My invention consists in a sheet metal culvert or drain having its end fitted with a novel reinforcing member.

It also consists in the novel fitting and arrangement of said reinforcing member, as I shall hereinafter fully describe.

My invention is applicable to culverts, such as are used for drainage under railroads, highways, or in other places where a durable culvert or drain pipe is required.

The objects and advantages of my invention will be fully set forth hereinafter, and will be better understood from an inspection of the accompanying drawings, in which—

Figure 1 is a side view, broken, of an end section of a culvert or of one end of a culvert, showing the reinforcing member in its seat, but not fully covered therein at its meeting ends. Fig. 2 is an end view of the same, showing the covering tongue bent home. Fig. 3 is a section, enlarged, on line $x-x$ of Fig. 2. Fig. 4 is a section, enlarged, on line $y-y$ of Fig. 2. Fig. 5 is a side view, broken, showing the application of the reinforcing member to a part circle culvert. Fig. 6 is an end view, partly in section, of the same.

In Figs. 1 and 2, the culvert shown is a full circle, and is made of corrugated sheet metal. Fig. 1 may indicate either one end of a culvert, or it may represent one end of one of the end sections of a culvert. In the former case each end of the culvert is to be fitted with the reinforcing member; and in the latter case but one end will have said reinforcing member, while the other end section of the complete culvert will have its free end provided with the reinforcing member, the intention in all cases being to reinforce both ends of the culvert.

In Figs. 1 to 4, the culvert is 1, and the reinforcing member is a rod 2. The end of

the culvert 1 is bent over at 3 to form a channel in which is seated the rod 2.

In order to make a proper joint where the sides of the culvert plate overlap and to cover the rod 2 where its ends meet, the innerlyng side of the culvert plate is cut in 60 from the end along a line above the edge of the outerlyng side, thereby forming a tongue 4; and the end of the outerlyng side is entirely cut away to the width of the overlap. When the rod 2 is so seated in the 65 bend 3 that its ends meet in the line of the upper edge of the outerlyng side of the culvert plate, as shown in Fig. 1, the tongue 4 is bent over to cover said meeting ends, as in Figs. 2 and 3.

In part circle culverts, such as are generally used in street work or where the head room is limited and a large water way is called for, the reinforcing rod 2 will be covered in the bend 3 of the part circle culverts 5 of Figs. 5 and 6.

It will be noted that in both culverts, full round and part round, when they are of the corrugated metal type, the channel formed by the bend 3 has for its inner portion the 80 bottom of a furrow of the corrugation.

By my invention I am able to provide a metal culvert or drain pipe of increased strength at the extremities, thereby guarding against the impact of debris, rock, etc., 85 or whatever would tend to distort the true shape of the ends and thus obstruct the water way. A culvert thus reinforced at its ends, especially one which is of comparatively large diameter and made of thin 90 sheets of metal and which would not of itself bear a load likely to be placed upon it, is thus made capable of sustaining heavy travel. This reinforcing rod also acts as a guard against the effects of rough handling 95 during shipping, transportation and installing which in most cases is hard to prevent, especially where the culvert sections are of large diameter and great length.

It is also to be noted that a reinforcement as herein disclosed is especially advantageous in a culvert made of corrugated sheets, where by reason of the corrugations the pipe itself is of much greater strength than its extreme ends. With an end reinforcing rod this difference will be eliminated and the end of the pipe will be of equal strength with its body. Moreover in

this corrugated type of culvert, by having for the inner portion of the peripheral channel the bottom of a furrow of the corrugation, the reinforcement is compact and does 5 not project unduly from the general surface of the culvert; it will not, therefore, be as liable to injury.

Having thus described my invention what I claim as new and desire to secure by Letters Patent is—

1. A sheet-metal culvert of the corrugated metal type having its end bent to form a peripheral channel, the inner portion of which is the bottom of a furrow of the corrugated metal and a reinforcing member seated in said channel.

2. A sheet-metal culvert of full round section with overlapping sides, the inner-lying side being cut in from the end to form 20 a tongue, and the corresponding portion of the outerlying side being removed, the end

of said culvert and the said tongue being bent to form a peripheral channel; and a reinforcing member seated in said channel.

3. A sheet-metal culvert of full round section with overlapping sides, the inner-lying side being cut in from the end to form a tongue, and the corresponding portion of the outerlying side being removed, the end of said culvert and the said tongue being 30 bent to form a peripheral channel; and a reinforcing member seated in said channel, and so disposed that its meeting ends are covered by said tongue.

In testimony whereof I have signed my name to this specification in the presence of two subscribing witnesses.

KARL JOHAN THORSBY.
